(57) **CLAIM**

The ornamental design for a display screen or portion thereof with graphical user interface, as shown and described.

DESCRIPTION

The file contains drawings of FIGS. 2, 3 and 5, executed in color. Copies of this patent with color drawings will be provided by the Office upon request and payment of the necessary fee.

FIG. 1 is a front view of a display screen or portion thereof with graphical user interface according to a first embodiment of our design;

FIG. 2 is a front view thereof according to a second embodiment, having select colored portions;

FIG. 3 is a front view thereof according to a third embodiment, having select colored portions;

FIG. 4 is a front view thereof according to a fourth embodiment; and,

FIG. 5 is a front view thereof according to a fifth embodiment, having select colored portions.

The dashed broken lines in the drawings represent the display screen or portion thereof and elements of the graphical user interface that form no part of the claimed design. The dash-dot broken lines represent a boundary to the claimed design and form no part of the claimed design.
